Primary Examiner — Catherine S Posthauer*Assistant Examiner* — Lynette Marie Sample(74) *Attorney, Agent, or Firm* — Boudwin Intellectual Property Law, LLC; Daniel Boudwin(57) **CLAIM**

The ornamental design for a can opening cover, as shown and described.

DESCRIPTION

FIG. 1 is a perspective view of a can opening cover, showing my new design;

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof; and,

FIG. 8 is a front perspective view thereof, shown in use with an exemplary can.

The broken lines are shown for the purpose of illustrating environmental subject matter of an exemplary can, and form no part of the claimed design.

1 Claim, 6 Drawing Sheets(56)
